CARPET OR THE LIKE SHAMPOOING
APPARATUS

William John McDonald, William Francis Cook, and Joseph Peter Raffe, all of London, England, assignors to Chiswick Products Limited, London, England, a British company

Filed Aug. 20, 1963, Ser. No. 303,225

Claims priority, application Great Britain, Aug. 20, 1962, 31,960/62

9 Claims. (Cl. 15—533)

The present invention concerns an appliance for shampooing carpets or the like of the type (hereinafter referred to as of the type set forth) wherein a foam-forming liquid detergent or like cleaning liquid is applied to the carpet.

In known appliances of the type set forth the liquid detergent is discharged from a tank directly onto a roller having a resilient surface (e.g. of a spongy material) the roller being mounted between a pair of brushes which extend alongside the roller. The appliance is supported on the roller with the result that the spongy roller is deformed. As the appliance is moved to and fro the portion of the roller which is deformed is continuously changing and the liquid detergent in the sponge material is thereby agitated and converted to a foam on or immediately adjacent the carpet with the risk and actual result in many cases that the liquid soaks into the carpet with consequent ill effects. It must be noted that such appliances are used mainly in unskilled manner e.g. by housewives. The foamed detergent is distributed on the carpet by the roller. The brushes scrub the foamed detergent (already produced and distributed over the carpet by the roller) into the pile of the carpet.

In contradistinction to the known appliance this invention provides that the detergent or the like is directed away from the roller and into the row of bristles of a brush extending along either or both sides of the roller. The detergent is preferably delivered to the row or rows of bristles substantially uniformly over the length of the brush and it is also preferred that the detergent is introduced to the bristles near the roots thereof where they are attached to a bristle-carrying member or brush stock.

An appliance for shampooing carpets will now be described, by way of example only, with reference to the accompanying drawings whereof:

FIG. 1 is a side view of the appliance,

FIG. 2 is a sectional view of the lower part of the appliance of FIG. 1 and to a larger size,

FIG. 3 is a part sectional view on the line III—III of FIG. 2,

FIG. 4 is a section on the line IV—IV of FIG. 2,

FIG. 5 is a section on the line V—V of FIG. 2, and

FIG. 6 is a section of the handle fitted to the appliance of FIG. 1 and to a larger size.

Referring to FIG. 1; the appliance comprises a tank 10 for liquid detergent, a detergent-applying unit 11 and a tubular handle 12 secured to the tank as later described. The unit 11 comprises a roller 13, a pair of brushes 14 (each of which extends alongside the roller 13) a liquid guide means in the form of a cover plate member 15 to overlie the roller and a duct 16 which extends along the roller 13 and which receives the detergent delivered from the tank. The appliance is moved to and fro across the surface of a carpet to be cleaned, the housewife or operator pushing and pulling on handle 12 to this end. The appliance is mainly supported by roller 13 which runs over the carpet so that the appliance is readily moved by the operator. The lower ends (the tips) of the bristles of brushes 14 engage the carpet with the result that the bristles are alternately deformed and thereby vigorously

2

agitate and thus foam the liquid detergent discharged into the bristles as hereinafter described.

The unit 11 comprises a hollow body member 17 of such flexible material that the ends 18 thereof may be deformed and separated slightly. The roller 13 and brushes 14 extend substantially between the ends 18 (see FIG. 3). The roller is rotatably mounted in a chassis frame 19 as later more fully explained. Each of the brushes 14 comprises a row of bristles carried by a brush stock or rib 20 which constitutes a long member of frame 19. The ends of ribs 20 are secured to cross members 21 and constitute therewith the frame 19.

The cover plate 15 is of inverted U-outline in cross-section (FIG. 2) and overlies roller 13, the plate 15 extending between the ends 18 of unit 11 and being centrally beneath duct 16. Plate 15 has integral end walls 22 which are removably attached to the cross members 21 (as later described in detail) so that the plate is carried by chassis frame 19.

20 The plate 15 has an upwardly-directed, central rib 63 which extends lengthwise of the plate and is immediately beneath duct 16. The long edges of plate 15 are outwardly flared (at 23, FIG. 2) and are presented to the bristles substantially at right angles to the bristles. The flared edges 23 touch the bristles in the region of the bristle roots immediately beneath ribs 20.

Tank 10 has a bottom 24 the underface of which carries duct 16. Bottom 24 has an integral tubular socket 25 which passes through bottom 24. Socket 25 receives 30 the lower end of tubular handle 12, the handle being secured therein by a screw 26. The socket 25 has a diaphragm which is formed with a valve seat 28 to receive a valve 29. The latter is mounted on a wire 30 which extends through the handle, the lower end of wire 30 having 35 a head 31 to engage a washer 32 which abuts valve 29. A cup member 33 abuts the upper end of valve 29. A spring 34 is received within member 33 to extend between the cup and a disc 35 that is held axially in position by a bead 36 formed on handle 12. The spring urges valve 29 to close upon seat 28. When wire 30 is pulled upwardly along handle 12 the valve 29 is opened to permit detergent to flow into duct 16. To this end the socket 25 is supported on bottom 24 by a pair of spaced lugs 37 (only one of which is shown) the socket 40 wall between the lugs being cut away to place the interior of the socket in communication with the tank immediately above bottom 24. The detergent flows from the tank 10 into duct 16 as shown by the arrows in FIG. 2.

As shown chain dotted in FIG. 3 duct 16 has a T branch 38. This receives the detergent from tank 10. The duct 16 has two spaced rows of holes 39 which extend lengthwise of the duct. Each row of holes lies on opposite sides of rib 63, the arrangement being that a stream of detergent is directed down each side of plate 15 towards the flared edges 23 which discharge the detergent as liquid into the upper parts or root region of the bristles.

The wire 30 is connected to a finger piece or trigger 40 (FIG. 6) which is immediately beneath a handle grip 41. 60 When trigger 40 is pulled upwardly against the action of spring 34 the valve 29 is opened and detergent is discharged into duct 16 and thence on to plate 15 and into the bristles of brushes 14. The cover plate is so constructed and arranged as to direct the detergent away from roller 13 (so that the detergent can not come into contact therewith) and into the brushes 14. Consequently the roller 13 serves no function in agitating the detergent received from the tank thereby to produce foam which is to be distributed on to the carpet. Instead the liquid detergent is delivered to the brushes and is agitated by the bristles to produce foam and the foam is spread on to

the carpet by the bristles. The detergent is received by the bristles as a thin stream of liquid directed into the upper part or root region of the bristles over the entire length of the brushes. The detergent rapidly and uniformly spreads through the bristles by capillary action. By these means a relatively small quantity of detergent may be used since it is uniformly introduced to the brushes and so applied to the carpet. The alternate deformation of the bristles as the appliance is moved to and fro rigorously agitates the detergent in the brushes and the detergent is effectively converted into a foam and the foam is applied to the carpet by the brushes with an effective scrubbing action. The application to the carpet of the detergent as a foam is assured because the liquid detergent is delivered to the root region of the bristle (i.e. furthest from the pile surface) and as the liquid detergent flows down the bristles it is agitated by the deforming bristles. The edge portions 23 are relatively thin and flexible (see FIG. 2) and being in engagement with the brushes are deformed by deformation of the bristles as explained above. Consequently contact between the brushes and edges 23 is continuously maintained in use.

Each cross member 21 of chassis frame 19 is formed with a pair of spaced, outwardly-directed bosses 42 (see FIGS. 3 and 5). Each boss is received in a hole in an end wall 18 of unit 11. As indicated the unit 11 has a body member 17 of flexible material. This may therefore be deformed to enable the bosses to be inserted into the holes, the end walls 18 springing back so that the chassis frame 19 is effectively secured to unit 11.

The bosses 42 extend to the inner side of the cross members 21 (see FIG. 3) and are hollow. Walls 22 of cover plate 15 have integral pegs 43 to enter the hollow bosses, the walls 22 of plate 15 being flexible for this purpose e.g. made of a synthetic resin material. In this way the plate is removably secured to the chassis frame 19.

It is an advantage that roller 13 is readily removable and replaceable e.g. for cleaning and maintenance. The roller 13 comprises a cylindrical body 44 of sponge-like material (e.g. cellular rubber or plastic) having a central axial hole to receive a tubular core 45. A cap 46 is fitted to each end of the core. Cap 46 has an integral stub shaft 47 which is to be received in a journal bearing 48 in each cross member 21. The bearing 48 comprises an arch member 49 (FIG. 2) against which shaft 47 is upwardly pressed and a pair of spaced fingers 50 depending from member 49. Each finger 50 has a rib 51, the ribs confronting one another. The fingers 50 are deformable and resilient the arrangement being that when the stub shaft 47 is pushed upwardly towards the bearing arch 49 the fingers separate to allow the shaft to pass the ribs. Similarly the stub shafts may be readily pulled away from the bearing arch. The operation of fitting and removing the roller does not require deformation of the roller (and its core) so that distortion of the roller does not result.

The handle grip is moulded from a synthetic resin material and has a central web or tongue 52. The upper end of handle 12 is slotted, as shown in FIG. 6 at 53, to receive the tip of the web 52 the slot 53 being toothed to bite the web and prevent withdrawal of the web and also to locate the handle in correct relative position to the tank 10. Alternatively the handle grip may be secured to the handle 12 by an adhesive, a web being formed on the inner wall of the handle grip to enter a slot in handle 12 and provide a location for positioning the handle relatively to tank 10.

The handle grip has a slot 54 by which the appliance may be hung up.

The trigger 40 is preferably a moulding having a rear face curved to fit the handle 12. The rear face has a T-section block 55 to receive the wire 30. The block 55 is passed through the larger hole of a key-hole slot in handle 12 and engages behind the slot where it is retained against withdrawal by the wire 30, spring 34 and valve 29.

Referring to FIG. 2; the duct 16 may incorporate a tube 56, shown chain dotted, the lower end of which passes through the bottom wall of the duct and the upper end of which is near the top most portion of duct 16. When duct 16 is full liquid is discharged therefrom through holes 39 and tube 56. When valve 29 is closed the inside of the duct is placed in communication with atmosphere through the tube 56 and it is thereby ensured that liquid remaining within duct 16 after valve closure can readily escape through holes 39. Consequently liquid detergent is not retained in the duct with the possibility that it slowly escapes after use of the appliance on handling the appliance prior to storage in a cupboard or the like or while stored away.

As described the roller may have a resilient surface (e.g. of a spongy material such as cellular polyurethane) but alternatively it may have a "hard" surface, for instance of a relatively rigid synthetic resin. Again the roller may have a resilient core and either a hard surface—such as a tube of rigid synthetic resin—or an impervious skin. Again, the elongated roller may be replaced by two or more axially spaced wheels (having resilient or hard surfaces) which are equivalent to the roller 13 that is provided primarily to support tank 10.

The roller may be mounted in rigid bearings as described or in spring-loaded bearings. The latter arrangement compensates for wear of the brushes.

Instead of a curved plate 15 to direct liquid detergent into each brush 14 it may be arranged (according to an alternative arrangement) that a plate is upwardly directed from one of the pair of brushes to overlie the roller with its upper edge. The latter is so disposed in relation to the duct 16 that the detergent discharged therefrom is deflected away from the roller and flowing downwardly of the plate is directed towards the root end region of the bristles. The bottom edge of the plate may be curved as described with respect to FIG. 2. The curved bottom edge touches the bristles so that the detergent is directed into the inter-bristle spaces. The top edge of the plate may be similarly upwardly curved to prevent detergent flowing over the edge to fall upon the roller.

We claim:

1. An appliance for shampooing carpets of the type set forth comprising a tank for liquid detergent, a valve to control discharge of liquid downwardly from said tank, control means to adjust said valve, walls downwardly directed from said tank, roller means carried by way of said walls to support the appliance for rolling movement over the carpet, at least one elongated brush extending substantially parallel with the axis of said roller means and spaced from the cylindrical surface thereof, and guide means to receive liquid discharged from said tank and direct such liquid out of contact with said roller means and on to said brush in the region of the bristle roots so that bristle agitation in use foams the detergent prior to its application via said brush to the carpet.

2. An appliance according to claim 1 wherein said guide means presents an edge portion in engagement with the bristles of said brush substantially along the whole length thereof and in the region of the bristle roots.

3. An appliance according to claim 2 wherein said edge portion in engagement with the bristles is flexible for deformation by flexure of said brush so as to maintain such engagement in use.

4. An appliance according to claim 1 wherein a brush extends along each of the pair of opposite sides of said roller means, said guide means comprises an inverted U-section member which overlies said roller means, extends over the length thereof, and presents each long edge portion thereof in engagement with the bristles of one of the brushes in the region of the bristle roots, and the liquid is discharged downwardly substantially centrally onto such guide member.

5. An appliance according to claim 4 wherein a frame 75 is removably clipped to said walls downwardly directed

from said tank and carries said brushes and said roller means, and said guide member is removably clipped to said frame.

6. An appliance as claimed in claim 4 wherein the U-member has a lengthwise-extending rib directed upwardly towards the tank from the uppermost portion of the member and the liquid is directed onto said member as two streams, one on each side of said rib.

7. An appliance according to claim 6 comprising a duct secured beneath the tank and extending lengthwise of said U-member to receive liquid discharged from the tank, said duct having two rows of holes from which the liquid is directed onto said U-member as two streams of liquid, one stream on each side of said rib.

8. An appliance as claimed in claim 7 wherein said holes are in the floor of the duct and there is a tube standing from the floor within the duct to connect the interior of the duct to atmosphere.

9. An appliance for shampooing carpets of the type set forth comprising a liquid tank, walls downwardly directed from the tank to define a hollow unit, an open rectangular frame removably secured to said walls, a roller removably mounted for rotation within said frame, a pair

15 of elongated brushes secured to opposite sides of said rectangular frame and substantially parallel with the axis of the roller, a handle connected to said tank, a duct secured beneath said tank and extending lengthwise of the roller, said duct having downwardly-directed holes, a valve to control discharge of liquid from the tank into the duct, manual control means for opening the valve for discharge of liquid into the duct and an inverted U-section member (which is flexible and resilient) removably carried by said frame to overlie the roller with each long edge of said member in engagement with the brushes, said U-member being beneath said duct to receive liquid discharged downwardly through the holes in said duct and to direct the liquid away from the roller to between the bristles of each brush in the region of the bristle roots so that bristle agitation in use foams the detergent prior to its application via each brush to the carpet.
